UNITED STATES PATENT OFFICE.

IRA P. ORLICK, OF PHILADELPHIA, PENNSYLVANIA.

DESIGN FOR A CHARM OR SIMILAR ARTICLE.

Application filed May 8, 1924. Serial No. 9,521. Term of patent 3½ years.

To all whom it may concern:

Be it known that I, IRA P. ORLICK, a citizen of the United States, residing in the city and county of Philadelphia, State of Pennsylvania, have invented a new, original and ornamental Design for Charm or Similar Article, of which the following is a specification, reference being had to the accompanying drawing, forming part thereof.

I claim:

The ornamental design for a charm or similar article as shown.

IRA P. ORLICK.
